UNITED STATES PATENT OFFICE

HUGH H. WARD, OF CHESTER, PENNSYLVANIA

METALLIC RECEPTACLE

Application filed June 18, 1928. Serial No. 286,150.

My invention provides improved means for securing a driven bung in the bung-hole of a sheet metal receptacle without interfering with the complete drainage of the receptacle, which may be reinforced adjacent to the bung-hole and thereby enabled to better withstand the shocks and strains incident to the driving and extraction of bungs.

10 My improvements are especially applicable to cask-like receptacles formed of sheet metal bent to form a curved body having heads permanently set in the ends thereof. In accordance with my invention, the bung-hole 15 is preferably formed in the body but may be formed in a head and the sheet metal surrounding the bung-hole is bent or crimped into an annular outwardly projecting ridge terminating in an inturned flange 20 and forming a reenforcing rib and a resilient bung-engaging lip. A reenforcing plate fixed to the inner wall of the body adjacent to the bung-hole is provided with an outwardly turned flange or collar housed between the ridge members and 25 yielding reenforcing the bung engaging lip, which is preferably fluted circumferentially to form a shallow channel or groove.

The characteristic features and advantages of my improvements will further appear from the following description and the accompanying drawings in illustration of a preferred embodiment of my invention.

In the drawings, Fig. 1 is an elevation of 35 a cask or barrel embodying my improvements; Fig. 2 is an enlarged fragmentary sectional view taken through the bung-hole; and Fig. 3 is an enlarged fragmentary plan view looking toward the bottom of the bung.

40 As illustrated in the drawings, my invention is applied to a barrel formed by rolling sheet metal into a cylindrical body 1 reenforced by circumferential ribs 2 and having its ends closed by heads 3, the edges of which 45 are crimped over the ends of the body.

The bung-hole 4 is preferably formed in 50 the curved wall of the body between the ribs 2 and is defined and surrounded by an annular outwardly projecting or convex ridge formed by an angularly bent web 5 and an

inturned resilient lip 6 spaced from the member 5 and bent to form a circumferential groove. A reenforcing plate 7 conforming to the contour of the body 1 is welded or riveted thereto around the bung-hole and 55 has an outwardly turned edge 8 forming an annular flange housed between the members 5 and 6 and engaging the apex or ridge of the latter on the face thereof opposite the circumferential groove.

A wooden bung 9 may be driven into the bung-hole without danger of distortion of the barrel and is firmly held against dislodgment by engagement of the protruding edge of the lip 6, the lip being yieldingly 60 reenforced by the collar 8.

Since the members 5, 6 and 8 project outwardly from the inner surface of the wall 1, the receptacle may be completely drained when the bung is removed without obstruction from such members.

Having described my invention, I claim:

A cask-like receptacle having a bung-hole in a curved wall thereof and surrounded by an annular ridge bent outwardly from said 75 wall and having an inturned grooved lip for the engagement of a driven bung and a reenforcing plate conforming to the contour of and fixed to the inner surface of said wall and having thereon an outwardly 80 turned collar housed between the members of said ridge and reenforcing said lip.

In witness whereof I have hereunto set my name this 21st day of May, 1928.

HUGH H. WARD.
